CLAIM

The ornamental design for a die holddown clamp, as shown and described.

DESCRIPTION

FIG. 1 is a left side perspective view of a die holddown clamp showing my new design, the broken line showing of a workpiece and bolt being for illustrative purposes only;

FIG. 2 is a right side perspective view wherein the adjustable swivel bracket has been moved to an alternate position;

FIG. 3 is a left side elevational view wherein the adjustable swivel bracket has been moved to an alternate position;

FIG. 4 is a top plan view thereof;

FIG. 5 is a bottom plan view thereof;

FIG. 6 is a right side elevational view thereof;

FIG. 7 is a front elevational view thereof; and

FIG. 8 is a rear elevational view thereof.
